RURAL FREE DELIVERY LETTER BOX

Thomas G. Wade, Greensboro, N. C.

Application July 21, 1932, Serial No. 623,841

4 Claims. (Cl. 232—34)

My invention relates to a rural free delivery letter box which is provided with a signaling flag, or flags, to indicate to the postman or to the owner of the box whether or not there is mail in the box to be removed from it by either the postman or the box owner. The object of my invention is to provide a mail box, the flag of which will be automatically operated at the time that any letters or packages are placed within the box.

10 A further object in my invention is to provide a box on which the signaling flag will be operated or placed into position to indicate that the mail is within the box, when mail is placed within the box without any separate or independent operation, the flag assuming an indicating position.

15 A still further object of my invention is to provide signaling flags which will be operated from within the box and will not become stuck or adhered in one position by reason of sleet and ice in winter-time, which difficulty offers a serious objection to the type of signaling flag which is now commonly in use on rural free delivery boxes.

20 Heretofore, rural free delivery mail boxes have been supplied with a signaling flag which is mounted on the outside of the box, and must be operated by the postman or the owner of the box at the time when mail is placed within the box or removed therefrom. Such boxes require an entirely separate and independent operation to place the signaling flag in a proper position to indicate either that there is mail in the box or that the box is empty. Very often the postman or the box owner neglects to place such a flag in the indicating position, with the result that a proper signal is not given either to the postman or the box owner and great inconvenience or loss of time is caused thereby.

25 It is the purpose of my improved mail box to provide a flag which must necessarily be operated at the time mail is placed within the box or removed therefrom, thereby positively and unfailingly giving a proper signal to the postman or to the owner of the box by indicating clearly that either the box contains mail or is devoid of mail.

30 In the accompanying drawings:

Fig. 1 is a prospective view showing the signaling flag in a position to indicate that there is no mail within the box.

35 Fig. 2 is a cross section of the mail box.

Fig. 3 is a section on the line 3—3 of Fig. 2.

40 Fig. 4 is a side elevation.

Fig. 5 is side elevation of modified form of signaling flags.

45 Fig. 6 is a standard mail box 2 is provided with door

4, which is hinged to the bottom of the box, which door when opened, hinges downwardly and opens an entire end of the box 2.

The resilient wire 6, extends through the box, in close proximity to the bottom thereof, from one side to the other in a position relatively near the front end of the box. Wire shaft 6, is provided with bent portions 8 and 10 within the box, which are adapted to bear upon the bottom 12, of the box and hold the wire in an adjusted position. Through the center of the box the wire 6 is bent into a loop 14, which loop is adapted to be struck by any mail which may be placed within the box or removed therefrom, thereby turning the wire shaft 6 through an arc varying from 90° to 180° and turning the upwardly bent end 16, on the outer end of the shaft 6, through a corresponding arc.

5 The end 16, of the shaft 6, is secured to connecting rod 18, which extends upwardly through 10 the guide 20, and is pivotally affixed at its upper end to integrally made flags 22 and 24, by means of the pivot 26, which is affixed to the upwardly extending arm 28, of flags 22 and 24. The flags 22 and 24, are pivotally secured to the bracket 15 25 30, by the pin 32. Bracket 30, is secured by rivets, or any convenient means, to the outside of the mail box 2.

20 When the shaft 6, is in position so that the loop 14, is in a vertical position, flags 22 and 24 30 will be in the position shown in Fig. 1. When mail is placed within the box by the postman, in order to place the mail therein it will be necessary to push against the loop 14, so that it will 35 assume the position shown in Fig. 4, during 35 which change the shaft 6 will be rotated through an arc of 90° and the upwardly extending arm 16, will turn through a corresponding arc of 90° pulling with it the lower end of the connecting rod 18. By means of the guide 20, which is approximately in the center of the connecting rod 18, the upper end of the connecting rod will travel through an arc similar to the arc through which the lower end of the connecting rod 18 is forced by the movement of the arm 16. As the 40 upper end of the connecting rod moves through an arc of 90° it carries with it the pin 26, which joins the connecting rod 18 with the arm 28, and thereby swings the flags 22 and 24, through an arc of 90° until they assume the position shown 45 50 in dot and dash lines in Fig. 4, with flag 22, extending above the top of the box.

If the mail box is empty and the owner thereof places mail in the box to be collected by the postman, he, the owner, will pull the loop 14, to 55

a forward position, thereby operating the flags 22 and 24 in exact reverse of the manner described above, so that the flag 24, will take an upward position rather than flag 22, as described 5 above.

In the modified form shown in Fig. 5, I provide two flags 34 and 36, which are mounted on long shafts or arms 38 and 40, which shafts are affixed approximately at right angles to one 10 another by means of a sector shaped plate 42, which is pivotally secured to the box 2, near the apex of said sector plate 42, by means of a shaft 44 which is rigidly secured to the plate 42, and which extends through the box 2, near the bottom thereof. The end 46 of the shaft 44 is bent upwardly on the outside of the box 2, and is pivotally affixed to the connecting rod 48, at one end thereof. The opposite end of the connecting rod 48 is pivotally secured to the link 50, 20 which is secured to a shaft 52, which extends through the box 2 and carries a plate 54 within the box.

As the plate 54 is moved through an arc of 90° in either direction from the position shown in 25 Fig. 5, the link 50 and the end 46 of the shaft 44 will be moved through a corresponding arc of 90°, thereby moving flags 34 and 36 through a corresponding arc of 90° so that either the flag 34 or 36 will be in a position above the top 30 of the box 2 to signal the postman or the owner of the box. It will be understood that flags 22 and 24, and flags 34 and 36 will be of different colors or different shapes so that it will be easy to determine which flag is in a position above box 35 2, thereby easy to determine which signal is intended to be given. It will be understood that I might make slight modifications in construction of this device without departing from the spirit of the invention or the scope of the claims.

I claim:

1. In a mail-box, the combination of signal flags pivotally secured thereto, a connecting-rod pivotally and slidably secured to said box, a sinuous shaft extending through said box in close proximity to the bottom thereof, a crank-arm secured to one end of said shaft and pivotally secured to the connecting rod, and means secured between the sinuous portions of the shaft for forming an obstruction to the entrance of the box. 5

2. In a mail-box, the combination of signal flags pivotally secured thereto, a sinuous shaft extending through the box in close proximity to the bottom thereof, a crank-arm secured to one end of said shaft, a connecting rod between 10 said crank-arm and said signal flags, and means for rotating said shaft to effect a pivotal movement of the flags. 15

3. In a mail-box, the combination of a plurality of signal flags pivotally secured thereto, a shaft extending through said box in close proximity to the bottom thereof, a crank-arm secured to one end of said shaft, a connecting rod pivotally secured at one end to said crank and at the other end thereof to said flags, means 20 secured to said shaft for turning same, and means associated with said shaft for holding the flags in a neutral position. 25

4. In a mail-box, the combination of a plurality of signal flags pivotally secured thereto, and means for placing either flag in a signaling position, said means comprising a shaft in close proximity to the bottom of said box, a crank-arm on one end of said shaft, a connecting-rod between said crank-arm and said signal flags, 30 and means within the box for turning the shaft to change the position of the flags. 35

THOMAS G. WADE.
